UNITED STATES PATENT OFFICE.

STEPHEN KRNA AND PAUL TURZIK, OF BINGHAMTON, NEW YORK.

AUTOMATIC GATE FOR RAILWAY-CROSSINGS.

1,140,168.

Specification of Letters Patent.

Patented May 18, 1915.

Application filed August 20, 1914. Serial No. 857,709.

To all whom it may concern:

Be it known that we, (1) STEPHEN KRNA and (2) PAUL TURZIK, (1) a citizen of the United States of America and (2) a subject of the Emperor of Austria-Hungary, residing at Binghamton, in the county of Broome and State of New York, have invented certain new and useful Improvements in Automatic Gates for Railway-Crossings, of which 10 the following is a specification.

This invention relates to new and useful improvements in automatic gates for railway crossings.

The primary object of this invention is to 15 provide a gate positionable adjacent a railway crossing and automatically operated to its closed and opened positions by the movement of the train upon the track.

The invention is designed to prevent accidents at railway crossings and automatically 20 closes a gate across the highway at both sides of the railroad track whenever a train is approaching thereon while the designed mechanism likewise automatically 25 opens the gates when the train has passed the highway crossing.

A still further object is to provide a trip 30 actuated gate member in connection with a railway crossing which may be connected to any desired number of distantly positioned similar gates for the simultaneous actuation thereof.

With these general objects in view and others that will appear as the nature of the 35 invention is better understood, the same consists in the novel combination and arrangement of parts hereinafter fully described, illustrated in the accompanying drawings and pointed out in the appended claims.

In the drawings forming a part of this 40 application and in which like designating characters refer to corresponding parts throughout the several views, Figure 1 is a plan view of a portion of a railroad track 45 adjacent the highway crossing and provided with the present invention, two of the gates being shown in their closed positions. Fig. 2 is a side elevation thereof with one of the gates illustrated by dotted lines in its 50 open position. Fig. 3 is a view of the mechanism casing with one side removed and in section longitudinally of the connecting tube casing with the gate broken away and in its open position. Fig. 4 is a similar view with the parts arranged with the gate

closed. Fig. 5 is a similar view adjacent one side of the casing and illustrating the electric switch for the signal lights, the gate being open. Fig. 6 is a transverse sectional view of the mechanism casing with the gate open. Fig. 7 is an enlarged detail view of the releasing trip mechanism. Fig. 8 is an enlarged detail view of the operating dog of the device. Fig. 9 is a side elevation with parts of the elements broken away of the wheel operated track trip, the same being shown in its inoperative elevated position. Fig. 10 is a similar view illustrating a wheel as operatively positioning the track trip in its lowered position. Fig. 11 is a top plan view of a portion of a rail provided with the track trip, the tube casing for the operating cable being shown in horizontal section. Fig. 12 is a transverse sectional view of the mechanism illustrated in Fig. 10. Fig. 13 is a modified form of connecting means between the track trip and the connecting cable. Fig. 14 is a detail view partly in top plan and partly in section showing the operating means for distantly positioning gates. Fig. 15 is a top plan view of the releasing trip illustrated in Fig. 7. Fig. 16 is a top plan view of the operating dog illustrated in Fig. 8. Fig. 17 is a central longitudinal sectional view 85 through one of the gates illustrating the signal lamps positioned therein. Fig. 18 is a side elevation thereof and Fig. 19 is a top plan view showing a plurality of tracks and highways each provided with gates 90 automatically actuated by a moving train upon a single one of the tracks. Fig. 20 is an enlarged inside view of a portion of the casing showing certain details of construction, and, Fig. 21 is a sectional view taken 95 through Fig. 20.

Referring more in detail to the drawings, it will be noted that the device broadly consists in positioning the gates 20 adjacent the opposite sides of the road bed of a railway such as 21 and in providing means for automatically closing the said gates to the horizontal position across the highway such as 22 when a train is approaching such highway upon the track and moving in the direction indicated by the arrow in Fig. 1, it being also intended that such train shall automatically return the gates to their open or perpendicular positions when the train has completely passed over the said highway.

The operating mechanism for each gate employed is housed within a similar casing 24 positioned adjacent the railroad track and at one side of the highway which crosses the same, the said casings preferably having a curved roof 25 for rendering the same better adapted for shedding storms. An operating shaft 26 is journaled in the upper portion of the casing 24 and at one end 10 thereof projecting exteriorly of the casing and upon which end the gate 20 is rigidly secured.

The gate 20 is tubular in form being provided with an inner bore 27. Within the bore 27, an electric signal lamp 28 is positioned which is adapted to be constantly burning in the night time and during the day if desired and being viewable through a white glass 29 in the outer face of the gate. Another similar lamp 30 is positioned within the bore 27 and is viewable through a green glass 31 in the same face of the gate and is electrically connected with a stationary contact 32 and a movable contact 33 mounted upon the inner face of an end wall 34 of the casing 24. A third signal lamp 35 is likewise positioned within the bore 27 and is viewable through a red glass 36 in the corresponding face of the gate while the lamp 35 is in electrical connection with a stationary switch member 37 and a movable switch member 38 carried by the end wall 34 at a point slightly beneath the contacts 32 and 33 heretofore referred to. The electrical connections between the lamp 35 and the fixed contact 37 and movable contact 38 consists respectively of the wires 84 and 85 while similar connections are afforded between the lamp 30 and the fixed contact 32 and movable contact 33 by the respective wires 83 and 82. The wires 80 and 81 are provided in the cable 46 for affording the lamp 28 with a permanent supply of electric current from a suitable source such as a battery (not shown). A finger 40 is rigidly secured to the power shaft 26 interiorly of the casing 24 and is adapted to engage the movable switch member 33 upon a downward closing movement of the gate and thus close the electric switch of the green signal lamp 30 when the gate is substantially half closed while thereafter, the finger 40 engages the movable contact 38 and closes the electrical switch for the red signal lamp 35 when the gate is substantially closed and thus providing for lighting all three of the signal lamps whenever the gate which carries the same is in its closed position. Each of the movable switch members 33 and 38 respectively are provided on their opposite sides with springs 41 which allow a slight return movement of the movable switch members after engaging the bottoms of the knife switch sockets 32 and 37 respectively 65 while the opposite or upwardly positioned

springs 41 of each of the movable switch members will engage an adjacently positioned stop 42 upon the wall 34 and thus return said movable switch members slightly downwardly after having been completely opened upon the return upwardly swinging movement of the finger 40. By this arrangement it will be seen that the closing of the gate automatically lights the two lamps 30 and 35 successively while upon an opening 75 of the gate such lamps are automatically extinguished. It will be understood that a source of electrical supply such as a battery (not shown) is in circuit with the respective connecting wires of the signal lamps 28, 30 and 35, and that the said slight return movements of each of the movable switch members places such members in the line of travel of the finger 40 for contact and actuation upon its next movement. 85

The power shaft 26 is provided with a circular disk 43 secured thereto and preferably provided with a rubber covering and being in constant engagement with the annular operating portion 44 of an alarm bell 90 45 carried within the casing. It will be seen that by this arrangement, upon any movement of the gate and the accompanying revolving of the shaft 26, the alarm bell 35 will be actuated, the operation of such bell 95 being similar to the tire contacted bicycle bells now commonly employed. A gear 47 is secured to the power shaft 26 and is in mesh with a smaller gear 48 positioned upon a transversely journaled shaft 49 within the 100 casing 24 and beneath the power shaft 26. A drum 50 upon the shaft 49 is provided with a cord 51 secured thereto and adapted to be wound thereon while a weight 52 is attached to the free end of the said cord. The 105 position of the gate being horizontal when closed as illustrated in Figs. 1 and 4, the cord 51 is then arranged to be in its wound position upon the drum 50 and with its weight 52 elevated as best shown in Fig. 4. 110 With the gears 47 and 48 unrestrained, the heft of the weight 52 is sufficient to turn the gears and the power shaft 26 thereby elevating the gate to its open position.

One of the rails 53 of the track is provided with a vertical opening 54 therethrough adapted to slidably receive a rod 55 upon the upper end of which a head 56 is positioned and adapted to move vertically within a socket 57 of the rail tread, it being noted that a plurality of rollers 58 are preferably provided projecting from the upper surface of the head 56 and adapted for contact by the passing wheel 59 of a train and resulting in placing the trip member so formed in its depressed position as illustrated in Fig. 10. 115 120 125

The casing 24 is provided with opposite openings 60 adjacent the bottom thereof and to which openings oppositely extending 130

tubular casings 61 are attached, each of the said casings 61 having an angular end member 62 extending beneath the adjacent track rail 53 and in alignment below the track trip 5 56 and 111 thereof.

Each extension 62 is provided with a circular disk 93 journaled therein and connected by a link 94 with the said trip rod 55. The disk 93 has a peripheral groove 95 with- 10 in which is secured one end of a cord 96, which cord passes over a pulley 97 at the connection of the casing 61 and its extension 62 and then extends the entire length through the casing 61 and after passing over 15 a pulley 98 has its free end secured to the lower side of the operating dog 99, which latter is pivoted to a bracket 100 upon the inner side of the casing 24. Upper and lower springs 101 are mounted upon the 20 bracket 100 and engage opposite faces of the dog 99, normally retaining the same in a substantially horizontal position and between adjacent ones of the teeth of the power gear 47.

25 A releasing trip 102 is mounted within brackets 103 carried by the casing 24 and is normally inwardly projected by an encircling spring 104 so as to engage between the adjacent teeth of the gear 47. A connecting cord 105 is secured to the dog 102 at one end and extends over upper and lower pulleys 106 and 107 respectively of the casing and has its opposite end attached to the cord 96 at a point slightly within the casing 35 end of the tubular member 61.

With the elements positioned as illustrated in Fig. 3 and with the gate in its open vertical position, the automatic operation of the device including the gate will be apparent. As each succeeding wheel of the train strikes the track trip during a passage of the train over the rail 53, it will be evident that the trip rod 55 will be rapidly reciprocated in a vertical direction, the car wheels 40 effecting the depression thereof while the extension spring 108 acting to promptly return the trip to its uppermost position. Each downward movement of the trip rod 55 gives a partial rotation to the disk 93 thus slightly winding the cord 96 there- 45 over and imparting a pull upon the cord 96 and drawing downwardly the operating dog 99 which by its contact with the adjacent tooth 109 of the gear 47 results in a slight turning of the gear as well as its power shaft 26 and upon which the gate is secured and with which it is thereby turned in its closing movement. The releasing of the track trip by a passing of the wheel 50 thereover slackens the cord 96 and allows the lower spring 101 to return the dog to its normal position, the said dog ratcheting upwardly over the next upwardly positioned tooth of said gear 47. The operation of the 55 trip being the same as that described when-

ever any wheel passes thereover, it will be seen that the passing of the train causes the operating dog to engage each of the succeeding teeth of the gear 47 until the interrupted gear portion 110 is reached and at 70 which time the gate will be lowered as shown in Fig. 4. During each tooth engaging movement of the dog 99, the releasing trip 102 is actuated for releasing the gear 47, such movement of the trip being effected by 75 reason of the pull exerted upon the cord 105 whenever the cord 96 is pulled and to which cord 96 the said cord 105 is attached, the trip 102 immediately returning to a locking position and engaging the next succeeding tooth of the gear 48.

From this detailed description the operation of the device will be evident so far as the automatic closing of the gate by the track trip is concerned as well as the manner of sounding the alarm bell 45 during any movement of the gate and also the automatic control of the electric signal lights 30 and 35.

A similar tripping member 111 is positioned upon the rail 53 at a point upon the track on the opposite side of the highway from the gate closing trip and the construction thereof as well as its operation being identical to that heretofore described, 95 it will be only necessary to note that the trip 111 is designed for the purpose of pulling the cord 112 upon each contact of a wheel with the said opening trip 111. The trip 56 being positioned first in the path of 100 travel of the passing train, is adapted to close the gate by pulling the cord 96 while the trip 111 being contacted by the same train after the train has passed over the highway, is adapted to release the trip 102 105 by pulling upon the cord 112 and thus allowing the weight 52 to return the gate to its open position as heretofore referred to, the cord 112 being attached to the releasing trip 102.

The releasing trip 102 is slidably mounted within brackets 103 carried by the casing 24 and is spring-pressed by means of the encircling spring 104 to normally hold the trip in engagement with the adjacent teeth 115 of the gear 47.

The gate 20 when closed is adapted to have its free end rest within a U-shaped bracket 115 positioned adjacent the track while the gate at its opposite and shorter 120 end is provided with a plurality of weights 116 acting as a counterbalance in assisting to return the gate to its open vertical position.

In Fig. 13 there is illustrated a modified 125 form of trip connecting means which consists in connecting the trip rod 55 pivotally with an angular rocker arm 117 and having the cord 96 secured to the other end of said rocker arm and it will be evident that either 130

of these forms of connections may be employed with either the closing trip 56 or the opening trip 111 of the device.

In connection with a crossing one casing 24 which is positioned at one side of the railway track is preferably alone adapted for direct actuation by means of the track trips and provided with the connecting tubular casings 61 while the same is adapted to synchronously operate identical mechanism in connection with an oppositely positioned one of said casings 24 and gate 20 by means of a transversely positioned shaft 118 extending beneath the railroad rails and journaled in brackets 119 of the sides 34 of said oppositely positioned casings and extending thereto. A tubular housing 120 is preferably provided for the shaft 118 and is secured between the said casings 24.

20 A sprocket wheel 121 is secured upon the shaft 49 of each casing and has a sprocket chain 122 extending thereover and also over a similar sprocket wheel 123 mounted upon the extended end of the shaft 118 within the 25 casing and in vertical alinement with the said wheel 121. Only that one of the casings 24 to which the trip cords communicate is required to be supplied with the releasing trip 102 or the operating dog 99 and all of 30 the other elements within the respective casings 24 being identical, it will be seen that the movements of the power shaft 24 and consequently the gate carried thereby will be uniform. In this manner, the gates 20 35 may be operatively positioned with respect to the track and across the highway as shown in Fig. 1 and simultaneously closed and opened by means of the closing trip 56 and opening trip 111 respectively.

40 As illustrated in Figs. 14 and 19, a casing 124 may be supplied for one gate 125, the latter being actuated directly by the closing and opening trips as heretofore described. The opposite gate 126 may be similarly actuated 45 while other gates 127 and 128 upon opposite sides of a neighboring track 129 are simultaneously operated by similar connections positioned within a tubular casing 130. Other gates 130' and 131 positioned adjacent 50 another highway may be similarly operated by a sprocket chain 132 connecting the operating mechanism of said gates 130' and 131 and the power shaft 133 within the said casing 130.

55 While the forms of the invention herein shown and described are what are believed

to be preferable embodiments thereof, it is nevertheless to be understood that minor changes may be made in the form, proportion and details of construction without departing from the spirit and scope of the invention as set forth in the appended claims.

What is claimed as new is:—

1. A crossing gate comprising in combination with a track rail having spaced perforations therethrough, of normally elevated wheel engaging trips vertically movable within said openings, a casing positioned adjacent the track, a power shaft within said casing, a gear secured to said shaft, a gate secured to an outwardly projecting end of said shaft, an operating dog pivoted within said casing and engaging the teeth of said gear, releasing means within said casing engaging said gear, operative connections between said dog and releasing means and one of said trips whereby said gear and power shaft and gate are turned in the gate closing direction during the passage of car wheels over the said trip, connections between said releasing means and the other one of said track trips and means for turning the said gear in the gate opening direction upon a disengagement of said releasing means.

2. A trip device comprising in combination with a rail having a vertical opening therethrough terminating at its upper end in a socket open at the tread portion of the rail, a rod slidably movable within the said opening, a convex head upon the upper end of the said rod and movably positioned within the said socket, a plurality of rollers journaled in the said head and projecting upwardly therefrom, a disk having a peripheral groove journaled beneath the said rail, a link pivotally connecting the lower end of the said rod with a radial point upon the adjacent face of the said disk, automatic projecting means for the said rod whereby the upper faces of the said rollers are normally resiliently supported above the rail tread and a gate actuating cord having one end thereof positioned and secured within the said disk groove.

In testimony whereof we affix our signatures in presence of two witnesses.
